Attorney

UNITED STATES PATENT OFFICE.

ALEXANDER S. PUTNAM, OF LOS ANGELES, CALIFORNIA.

BED-RAIL FASTENER.

1,423,628.

Specification of Letters Patent. Patented July 25, 1922.

Application filed October 1, 1921. Serial No. 504,556.

To all whom it may concern:

Be it known that I, ALEXANDER S. PUTNAM, a citizen of the United States, residing at Los Angeles, in the county of Los Angeles and State of California, have invented new and useful Improvements in Bed-Rail Fasteners, of which the following is a specification.

My invention relates to a bed rail fastener, the principal object of my invention being to generally improve upon and simplify the construction of the existing forms of bed rail fasteners, to provide a relatively simple and efficient fastening means that may be advantageously utilized between metal side rails and the wooden posts of a bed frame; further to provide a construction that is self-tightening, that is, the parts being constructed so that they are automatically drawn into close engagement with each other when properly assembled, thereby providing a firm, strong and substantial structure between the side rail of the bed and the corner post of the bed frame.

A further object of my invention is to provide a rail, simply and practically constructed, wherein the side rail of the bed may be turned end to end, so that when it is arranged with its horizontally disposed flange at the bottom and inwardly presented, it will serve as a support for transversely disposed spring or mattress slats.

With the foregoing and other objects in view my invention consists in certain novel features of construction and arrangement of parts that will be hereinafter more fully described and claimed and illustrated in the accompanying drawings in which—

Fig. 1 is a perspective view of a bed rail fastener of my improved construction;

Fig. 2 is a plan view of the fastening device of my improved construction and showing the corner post of the bed frame in horizontal section;

Fig. 3 is a perspective view of the fastening member that is secured to the corner post of the bed frame;

Fig. 4 is a perspective view of the end portion of the side rail of the bed and which is equipped with a part of my improved fastening device;

Fig. 5 is a plan view of the part of the device seen looking in the direction indicated by arrow 5 in Fig. 4.

Referring by numerals to the accompanying drawings which illustrate the practical

embodiment of my invention, 10 designates the wooden corner post of a bed frame; 11 the head rail or panel that is disposed between the corner posts and 12 a side rail that is preferably formed from a suitable section of angle iron. The part of the fastening device that is secured to the corner post 10 comprises a substantially rectangular plate 13 of suitable sheet metal in the upper corner and rear portions, on which are formed apertures 14 that are adapted to receive metal dowel pins 15, when the rear portion of the plate is positioned in slot 16, that is formed in the corner post 10. This manner of fastening the plate 13 to the corner post eliminates the use of fastening devices, such as screws and bolts and which latter tend to work loose, while in service. Pressed from the body of plate 13 and extending at right angles thereto, is a vertically disposed flange 17, which, when the plate 13 is secured to post 10, occupies a shallow recess 18, that is formed in the face of said corner post and this flange serves as a bearing for the plate 13 on the post, as well as for a bearing for the rear edge of the part of the fastening device that is secured to side rail 12.

Formed in the upper forward portion of plate 13 is an inwardly extending slot 19 and extending downwardly and rearwardly from the rear end thereof is a slot 19', the lower portion of which terminates a short distance in front of the central portion of flange 17. Formed integral with the lower front portion of plate 13 is a laterally projecting angle bracket 20, the horizontal flange of which is rearwardly presented and said bracket serves as a support and point of attachment for the end portion of end rail 21 and which latter is preferably constructed from a piece of angle iron. It will be understood that both ends of end rail 21 are connected to the bracket 20 of plates 13, and thus the two plates that are connected to a pair of the corner posts 10 are rigidly connected to each other and a firm and substantial structure is thus produced.

The end portion of the side rail 12 is provided with a longitudinally disposed slot 22 between the vertical and horizontal flanges and positioned and directly beneath this slot and spaced apart a slight distance from the end portion of the vertical flange of said rail 12 is a plate 23, the rear portion of which is bent latterly a slight distance so that it bears directly against the inner face

- of the vertical flange of said rail 12, and said bent rear portion of said plate being secured to the vertical flange of the side rail by rivets 24 or like fastening devices.
- 5 Formed integral with and projecting upwardly and downwardly from the upper and lower corners of plate 23 and immediately adjacent to its outer end are lugs 25, having inclined rear edges 26 and the upper one 10 of these flanges project upwardly through the outer portion of slot 22. Seated in the upper outer portions of plate 23 and vertical flange of rail 12 is a pin or rivet 27, the ends of which are riveted down against the outer 15 faces of said plate 23 and the vertical flange of rail 12. (See dotted lines Fig. 5.)
- When the side rail 12, carrying the plate 23, is secured to the corner post attachment, the parts are manipulated so that the upper 20 portion of plate 13 occupies a position between plate 23 and the end of the vertical flange of side rail 12, and with the rivet 27 positioned in the downwardly and rearwardly projecting slot 19'. As the parts are 25 forced into engagement with each other the rivet will ride down the edges of the inclined slot 19', thereby drawing the parts firmly together with the end of plate 23 bearing against flange 17 that is arranged 30 on the face of post 12 and this drawing together action is enhanced by the bearing of the inclined rear edge 26 of the lower lug 25 against the rear edge of the end rail 21. Thus the parts of the fastening device are 35 very firmly secured to each other when properly assembled and the parts cannot be detached until side rail 12 is engaged and lifted so as to withdraw rivet 27 from the slots 19 and 19'. When it is desired to utilize 40 the side rail for supporting transverse slats and which latter support a spring or mattress (not shown) the side rail 12 is turned end for end and fastening devices on the ends of said side rail are engaged with 45 the plates 13 in the manner hereinbefore described, and when so positioned the horizontally disposed flange of the side rail projects inwardly from the lower portion of the vertically disposed flange, thereby providing 50 a wide and substantial support for the ends of the slats or the like.
- A bed rail fastener of my improved construction is comparatively simple and may be easily and cheaply produced, and is especially applicable for the attachment of metal side rails to wooden corner posts, permits 55 the side rails to be reversed so as to produce supports for transverse slats and said fastening devices are very strong and substantial, and very effective in performing their intended functions. It will be understood that minor changes in the size, form and construction of the various parts of my improved bed rail fastening device may be made and substituted for those herein shown 60 and described without departing from the spirit of my invention, the scope of which is set forth in the appended claims.
- I claim as my invention—
1. In a bed rail fastener, a plate secured 70 to the corner post of the bed frame, which plate is provided with an inverted L-shaped slot, a bracket projecting laterally from said plate, an end rail affixed to said bracket and spaced from the corner post, a side rail, a plate secured to the end thereof, means seated in said side rail and in the plate carried thereby for engagement in the slot in the first mentioned plate, and lugs formed on the upper and lower corners of the plate 75 that is secured to the side rail, the lower one of which lugs is adapted to be positioned between the end rail of the bed frame and the post.
2. In a bed rail fastener, a corner post, a plate, having a portion seated in a slot in said post, means for securing said plate to said post, a flange projecting laterally from said plate and bearing against the outer face of the post, there being an inverted L-shaped 80 slot formed in the outer portion of said plate, a side rail, a plate secured to the end of said side rail, and a rivet seated in said plate and side rail and adapted to occupy the slot in the first mentioned plate. 85
3. In a bed rail fastener a post, a plate carried by said post, and projecting outwardly therefrom, a laterally extending bracket on said plate, an end rail affixed to said bracket and spaced at its rearward edge 90 from said post, said plate formed above the bracket with an open ended, downwardly inclined slot, a side rail, a pin on said side rail adapted to be engaged in said slot and a plate on said side rail arranged to abut 95 against the post when the pin is engaged in the slot, said plate being formed with lugs projecting upwardly and downwardly from the side rail, either of which lugs is adapted to extend between the end rail and the post 100 in wedge engagement therewith. 105

ALEXANDER S. PUTNAM.
